UNITED STATES PATENT OFFICE.

JOHN J. SIMMONS, OF SAN JOSE, CALIFORNIA.

DISHWASHER.

Application filed December 15, 1927. Serial No. 240,228.

This invention relates particularly to a device for use in washing drinking vessels.

It is one object of the invention to provide a device of the character indicated particularly adapted for the washing of drinking glasses, goblets and tumblers of all sizes, kinds and shapes.

It is another object of the invention to provide a device of the character indicated 10 that will effectually wash a large number of vessels at the same time, and one that is simple in form and construction, economical to manufacture, and highly efficient in its practical application.

15 It is also an object of the invention to provide a novel form of holder for each individual vessel, whereby the vessel will be held against movement while being washed and yet not clamped or otherwise fastened in position, and so formed and constructed that a vessel may be quickly positioned therein or removed therefrom.

It is still another object of the invention to provide an efficient rack for the several 25 holders and a suitable tub adapted to be used in conjunction with the rack.

In the drawing:

Figure 1 is a side elevation of a double washer embodying my invention, part broken 30 away and partly in section.

Figure 2 is a detail plan view on 2—2, Figure 1.

Figure 3 is a detail plan view on line 3—3 of Figure 1.

35 Figure 4 is a section on line 4—4, Figure 1.

Figure 5 is a perspective view of one of the vessel holders and a portion of the rack.

Figure 6 is an enlarged detail section 40 through the shaft support.

Figure 7 is a perspective illustration of a portion of the upper end of one of the retaining bars and the means for securing the same to the rack.

Figure 8 is a side view of a portion of the 45 lower end of one of the retaining bars and its supporting means.

Referring now more particularly to the drawing, I show at 1 a tub lined with a non-corrosive metal 2 and supported on legs 3. 50 In the center of the bottom of the tub is formed an opening 4, and the tub lining is formed into an upstanding cone over this opening as shown at 5 and fitted with a suitable bearing at its upper end as indicated at 6. A hinged cover is mounted on the tub as shown at 7.

Arranged below the tub 1 is a cross-bar 8, and mounted on this bar is a motor 9 operating a drive shaft 10 mounted in bearings 11 and fitted with a worm gear 12. Meshing 60 with gear 12 is a gear 13 on shaft 14, the latter passing upwardly through bar 8 and fitted with finger 15. The finger 15 is provided with a cam surface or edge 16 on the side directed forwardly of its path of travel, the latter being indicated by the arrow 17.

At 18 is shown a rack operating shaft mounted in parallel relation to shaft 14 and spaced a distance therefrom and in axial alignment with the bearing 6. This shaft 70 passes downwardly through bar 8 and has an annular collar 19 mounted thereon seated upon balls 20 in a cup 21 mounted on the upper side of bar 8 as shown. Mounted on shaft 18 to rotate therewith and in the plane 75 of the finger 15 is a yoke 22. This yoke is so arranged that when the finger 15 is rotated from the position shown in solid lines in Figure 2 the tip of the finger will engage the inner edge of the yoke on one side and swing 80 it into the position shown in dotted lines at 23. When this point is reached the shoulder of the finger, as 24, engages the inner edge of the opposite side of the yoke so that the cam surface 16 will swing the yoke into the position shown in dotted lines at 25. In this position the shoulder 24 engages the first indicated edge of the yoke and reverses its movement. In this manner the continued revolving of the finger 15 imparts an oscillatory 85 movement to the shaft 18. The upper end of the shaft 18 is squared as indicated at 26.

The rack comprises a top member 27 seated upon the squared upper end of shaft 18 so as to rotate therewith, and provided with a 90 handle 28. This member 27 is preferably hexagonal in shape and has a depending wire 29 mounted upon each corner, each wire having a vertical portion and an outwardly directed horizontal portion several times repeated to form a stepped arrangement. The corresponding corners of the several stepped wires are joined by horizontal wires as 30 and 31 whereby to form a rigid one-piece rack. The lower end of each wire 29 is extended 100 outwardly a distance and then turned upwardly as at 32 to engage the socket 33 in the lower end of a wooden bar 34. This bar 34 parallels the angle of the adjacent wire 29 and is supported at its upper end by a wire 110 loop 35 swingably mounted on the rack as at 36.

Each of the steps in the rack above described, forms a seat for a vessel holding basket. The basket comprises a wire 37 arranged parallel with a wire 30 and having its 5 two ends bent into parallel loops as 38 and 39 and terminating in small loops 40—41 engaging the wire 30. A wire 42 is mounted on the loops 38—39 and extends a distance therebeyond to engage the adjacent wires 29 10 to function as stops and prevent the basket from swinging inwardly of the rack. In plan view the wire 37 is angularly arranged relative to the supporting wire 30 thereby making the end loop 38 smaller than loop 39, and 15 parallelly arranged relative to loop 38 are a number of spaced loops 43, 44, 45, 46, 47. Connecting the last loop 47 with the loop 39 at the larger end of the basket are wires as 48. By means of this construction a goblet 20 or glass of any size or form may be placed in a basket and securely held there through the engagement of its foot piece with the transverse loops 43—47. A tumbler, or glass without a foot or stem, is held in the basket by the 25 wood bars 34.

Assuming that the device has been constructed as above described and water placed in the tub 1, the rack is filled with glasses in in whatever form or size they come to hand, 30 a basket of suitable size being found for every glass. The glasses are placed in the several baskets with their stem ends directed toward the smaller end of the baskets so that their open ends may all be pointed toward 35 the larger ends of the baskets. The rack is now placed in the tub 1 and on the shaft 18, the cover is closed and the motor started. The reciprocating movement of the shaft is of course imparted to the rack and the said 40 rack and the glasses thereon are swung back and forth in the water in such a manner as to thoroughly cleanse and wash each one.

The means for securing the oscillatory movement is important because the action of the finger 15 is such that one movement (into position 23) is more rapid than any other movement of the yoke and this is effective in securing the fullest cleansing effect of the agitated water. 45

The loops 40—41 of each basket are preferably formed in such a manner that the basket can be unhooked from the wire 30, and of course this connection permits the basket to be swung into and out of position when desired in placing or removing glasses. 50

It is to be understood, of course, that while I have herein shown and described but one specific embodiment of the invention, changes in form, construction, and method of assembly and operation may be made within the 55 scope of the appended claims.

I claim:

1. In a dish washer, a rack, a plurality of baskets without end walls mounted thereon, and means mounted on the rack adjacent the 60 ends of the baskets to prevent ejection of dishes from the baskets.

2. A basket comprising a wire having both ends bent into parallel loops terminating in means for mounting the same on a rack and a 70 straight intermediate portion, a second wire disposed parallel to the straight intermediate portion of said first wire and connecting the loops, a plurality of wires connecting said second wire and the straight intermediate 75 portion of said first wire and formed into loops arranged in spaced and parallel relation to the first loops, and a plurality of wires disposed parallel to the second wire and connecting one of the first mentioned 80 end loops with one of the last mentioned loops.

JOHN J. SIMMONS.
